BOTTOM HOLE OIL TREATING INJECTOR

Purdy L. Sisson, Oklahoma City, Okla., assignor to Automation Oil Corporation, Oklahoma City, Okla., a corporation of Oklahoma

Filed Feb. 10, 1964, Ser. No. 343,740

11 Claims. (Cl. 166—177)

This invention comprises a novel and useful bottom hole oil treater injector and more specifically pertains to a device for introducing a chemical treating agent into the oil entering a tubing string through which a well is being produced and for effectively mixing this treating agent with the oil prior to the entry of the latter into the tubing string.

A frequent problem encountered in the production of oil from wells arises from the forming of paraffin incrustations upon the pumping rods within the tubing and other parts of a pump or flowing well; and from the ingress of sand with the produced oil into the tubing string, and the like with resultant wear upon the parts thereof. It is therefore the general purpose of this invention to provide a means for largely overcoming the above-mentioned difficulties.

A primary object of the invention is to provide a device for effectively overcoming the problem of paraffin incrustations upon the rods, tubing and other parts of a pump or flowing well.

A further object of the invention is to provide a device which will effectively remedy the problem of sanding in a flowing well or pump 12.

A still further object of the invention is to provide a device for introducing a chemical treating agent, for various different purposes, into the oil prior to or during its entry into the filtering unit of the tubing string.

Still another object of the invention is to provide a filtering unit enabling the accurate construction of filter orifices of a predetermined relatively small size as in the order of one fifteen thousandths (1/15,000) of an inch.

Still another purpose of the invention is to provide a filtering unit in accordance with the immediately preceding object having a relatively great filtering capacity.

Still another purpose of the invention is to provide a filtering unit in accordance with the immediately preceding object having a relatively great filter capacity.

An additional object of the invention is to provide a filtering unit in accordance with the foregoing objects having means for effectively treating the filter in situ, without the necessity for pulling the tubing string in order to obtain access to the filtering unit.

Still another purpose of the invention is to provide a device in compliance with the preceding objects which shall be capable of injecting or introducing not only paraffin dissolving agents but other chemical treating agents such as heating agents and the like at the lower end of the tubing string for treating the oil passing therethrough.

Yet another purpose of the invention is to provide a device which shall be capable of being easily installed when a well cleaning job is being performed, and may remain in place when the pump is subsequently pulled for servicing and the like.

An additional object of the invention is to provide a device in accordance with the preceding objects wherein an oil treating unit for efficaciously mixing a chemical treating agent with the oil is provided consisting of no moving parts, and shall be constructed of standard units or sections capable of installation in series in any desired quantity to obtain varying treating capacities.

Yet another important object of the invention is to provide a device in accordance with the preceding objects wherein the units of the treating unit shall be interchangeable.

2

able to specifically adapt the unit to handle and treat oils of predetermined different gravity ranges.

A further specific object of the invention is to provide a novel and improved filter unit which shall afford a relatively large filter capacity and wherein any desired range of filter orifice size may be obtained.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a somewhat diagrammatic view partly in elevation and partly in section of an oil treating device in accordance with this invention and with the well casing or bore of a producing well being shown in phantom therein;

FIGURE 2 is a horizontal sectional view taken upon an enlarged scale through the oil treating sub and substantially upon the plane indicated by the section line 2—2 of FIGURE 1;

FIGURE 3 is an exploded view of the treating sub including the treating unit and the filtering unit, taken partly in elevation and partly in vertical section and substantially upon the plane indicated by the broken section line 3—3 of FIGURE 1;

FIGURES 4—6 are detail views of the oil treater unit, being taken in horizontal section substantially upon the planes indicated by the section lines 4—4, 5—5 and 6—6, respectively of FIGURE 3;

FIGURE 7 is a detail view taken upon an enlarged scale in vertical section substantially upon the plane indicated by the section line 7—7 of FIGURE 4 and showing further details of the internal construction of the treater units of the invention;

FIGURE 8 is a detail view in perspective of one of the jet nozzle units of the injecting means of the invention;

FIGURE 9 is an enlarged view in vertical central section through the novel filtering unit of the invention and showing the injector means disposed therein;

FIGURE 10 is an enlarged fragmentary view similar to FIGURE 9 but showing a modified construction by which a chemical treating agent is introduced directly into the filtering unit by the injector means disposed therein; and

FIGURE 11 is a detail view in perspective of a portion of the filtering units of FIGURES 9 and 10 and showing the construction thereof.

Referring first to FIGURE 1 it will be observed that a well bore which may be cased or uncased as desired, is indicated in phantom by the numeral 10 and extends into an oil productive formation from which oil is to be produced. Indicated at 12 is a tubing string having interposed therein or secured to the lower end thereof an oil treating sub indicated generally by the numeral 14. Shown disposed in the tubing string 12 immediately above the oil treating sub 14, as shown best in FIGURE 3, is a tubing pump including a pump barrel and casing 16 in which is reciprocated a pump rod string 18 by any suitable means at the surface, not shown, and which at its lower end is provided with any conventional form of reciprocating pump plunger 20 having a traveling valve assembly 22 of any desired type therein. At the lower end of the pump barrel 16 there is provided the usual standing valve assembly indicated generally by the numeral 24 and which likewise is of any suitable design.

Referring again to FIGURE 1 it will be observed that the treating sub 14 includes as component elements thereof an oil treater unit designated generally by the numeral 26 and which is supported by and in communication with the lower end of the tubing string 12 together

with an oil filtering unit indicated generally by the numeral 28 and which is secured at the lower end of the oil treater unit 26.

The sub 14 is of the same diameter as that of the tubing string to which it is connected so that it will be moved therewith into and out of a well casing as desired.

Referring now more specifically to FIGURE 3 it will be further observed that an injector means is provided for introducing various chemical treating agents into the sub 14 at the lower end thereof for mixing with the oil passing through the sub and into the production tubing 16. The injector means includes a supply conduit 30 which extends to and communicates with any suitable source of a chemical treating agent at the surface, not shown, and whose lower portion enters into the sub 14 through a side wall thereof and is provided with sets of nozzles with each assembly of such nozzles being indicated generally by the numeral 32 as shown in detail in FIGURE 8. The nozzles are disposed within the sand filter unit 28 and serve to introduce various chemical treating agents into the oil passing into the filtering unit and passing therefrom into the treating unit 26 from thence into the tubing string.

The present invention envisions the use of various chemical treating agents. The very important chemical agent employed is any suitable agent capable of dissolving paraffin as the latter precipitates out of the oil passing from the formation into the well bore so as to preclude the depositing of this paraffin in the form of encrustations upon the inside of the tubing string, upon the pump rods, and the like. The function of the injector unit is to homogeneously intersperse the treating agent throughout the oil in the filtering unit so that when the oil with the added treating agent reaches the treater unit 26, it will be more intermittently and thoroughly mixed therewith in that unit prior to its passage to the tubing string.

It is contemplated also that other treating agents may be provided for various purposes including agents for varying the gravity of the oil to facilitate its production, heating agent operable to effect an increase in temperature of the oil and thereby enable asphaltic and other heavy oils to be more readily produced from the well.

Referring again to FIGURE 3 it will be observed that the supply conduit 30 has a portion as at 34 which passes through the wall of the tubing string 12 and into the pumping chamber 36 and from thence through the pump barrel seating member or seating packer 38 which abuts against the upper end of the treater unit 26. From thence, in a manner to be subsequently described, the supply conduit 30 extends downwardly through the treater unit and terminates within the filtering unit in a series of nozzle assemblies 32 therein.

As shown best in FIGURES 3 and 7, the treater unit 26 includes a cylindrical housing 40 in which is disposed a series of vertically spaced alternate baffle units 42 and screen units 44 in vertically stacked relation extending throughout the length of the housing 40 of the treating unit 26. It will be observed that each of the baffle and screen units consists of a cylindrical open-ended body or wall 46 having a transversely disposed plate 48 for the baffles 50 for the screens disposed intermediately thereof. Referring especially to FIGURE 6 it will be observed that each of the screen plates 50 is provided with a plurality of perforations 52 disposed uniformly across its area and of an appropriate cross-sectional area for a particular gravity of oil which the device is adapted to treat. The baffle plates 48 on the other hand are provided with a plurality of openings 54 therethrough, with a baffle element 56 rising from the rim of each of the openings. It will be observed that the baffle elements 56 of adjacent baffle plates 48, are reversely inclined so as to reverse the direction of rotation of fluid passing through the treater unit as it passes each baffle plate.

Thus, an intimate mixing of the chemical treating agent which was added to the oil in the filter unit and below the treater unit is effected in the latter.

It will also be noted that there is provided a hollow central arbor 56 extending through the treater unit and that each of the baffle and screen plates are centrally apertured to surround and encircle this arbor, there being provided spacer sleeves 58 between adjacent plates.

The previously mentioned supply conduit 30 after entering the interior of the treater unit passes downwardly through the arbor 56 and emerging from the lower end of the latter enters and extends throughout the vertical height of the filter unit 28.

Referring now to FIGURE 8 it will be observed that the conduit 30 emerging from the arbor 56 into the filter unit 28 is provided with vertically spaced joints 60 from which project radially disposed arms 62 each carrying a conical-shaped spray-head 64 thereon. As shown in FIGURE 2, there are provided in vertically spaced relation throughout the interior of the cylindrical hollow body forming the filter unit 28 a plurality of supporting spiders 66 each surrounding and embracing the supply conduit 30 and centering it with respect to the filter body. Thus, the various nozzle assemblies 32 are centered and supported within the filter unit.

Reference is now made specifically to FIGURES 9-11 for an understanding of the construction of the filter unit forming an important feature of this invention. In order to obtain filtering orifices of any desired degree of fineness for preventing the ingress of very fine grained sands from the oil well, the filter body is formed by a plurality of rings 70 disposed in vertically spaced relation with respect to each other. The annular spaces 72 between the rings comprise the filtering orifices of the filtering unit and extend throughout the entire circumference of the rings thus providing the maximum area of filtering openings for the filter unit.

In order to secure the rings 70 in fixed and precisely spaced relation, there are provided as shown in FIGURE 11 a plurality of axially extending rods or other rigid elements 74 which are welded or otherwise bonded to the interior surface of each of the rings in circumferentially spaced relation thereabout to thus rigidly unite the rings together into a rigid assembly. The upper and lower ends of the rods are also bonded to externally threaded coupling members 76 and 78 at the upper and lower ends of the filtering unit and by which the latter is respectively secured to the lower open end of the treater unit 26 as by a coupling sleeve 80 and to a lower shoe or nipple 82 which is provided preferably with a closure plug 84 at its lower end. By means of the rigidifying axially extending rod 74, it is possible to very precisely space the rings from each other to obtain any predetermined spaces 72 therebetween. In some instances, these spaces may be on the order of one fifteen thousandths of an inch ($\frac{1}{15,000}$).

In the arrangement shown in FIGURE 10, the supply conduit is shown as having a portion 86 extending through the coupler 80 by which the treater unit 26 is secured to the filter unit 28. Thus, in this form of the invention the treating agent is brought by the supply conduit directly into the filtering unit itself thus avoiding the necessity of passing it through the treater unit 26. In some instances, the treater unit may thus be omitted and the filtering unit relied upon as a means for mixing the treating agent with the incoming supply of oil.

The invention is equally applicable to producing wells either which flow by their own pressure and thus do not require the presence of a tubing or other pump or wells which are produced under the action of a tubing pump.

The invention enables a very precise screening action together with the introduction of chemical treating agents into the oil after it has passed into the interior of the filtering unit. There is thus obtained a very intimate and effective mixing of the chemical treating agent with the oil before the latter enters the tubing string.

When it is desired to clean out the filter, this may

be effected by injecting through the supply conduit 30 the cleansing agent under a sufficiently high pressure to cause it to spray out against the interior of the filtering unit and thus cleanse the spaces 72 from the interior of the filtering unit. Consequently, it is not necessary to pull the tubing string in order to flush out the filtering unit.

The device can be readily installed at the end of a tubing string especially when the well is being worked over. When once installed it is no longer necessary to remove the stringer and filtering units when it is desired to pull the pump string in order to service the pump.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A bottom hole oil treating device comprising in combination with a tubing string through which oil is produced an oil treater unit mounted upon the lower end of said tubing string and communicating therewith, means introducing an oil treating chemical agent into the lower end of said treater unit for mixing with the oil passing therethrough, said treater unit comprising a plurality of vertically spaced alternate screen and baffle units within said treater unit with adjacent baffle units having oppositely directed baffles thereby effecting reversal of flow of the oil passing through successive baffle units.

2. An oil treating device comprising in combination with an oil flow tubing string an oil treating sub interposed therein, said sub comprising an oil treater unit having its upper end communicating with and supported by said tubing string, an oil filter unit mounted upon and communicating with the lower end of said treater unit and having an inlet end at the lower end of said tubing string, an injector means introducing an oil chemical treating agent into said filter for mixing with the oil passing through said sub, said treater unit including a plurality of vertically spaced alternate screen and baffle units with adjacent baffle units having oppositely inclined baffles thereby effecting a reversing flow of the oil passing through said treater unit.

3. The combination of claim 2 wherein said screen and baffle units each consists of a cylindrical wall having a transverse plate therein intermediate its ends, the plates of said screen units being each provided with a multiplicity

of apertures, the plates of said baffle units each having a plurality of openings therethrough with said baffles being each mounted upon the periphery of one of said openings.

5 4. The combination of claim 3 including an arbor extending axially through said treater unit, each of said plates being mounted upon and encircling said arbor.

5 5. The combination of claim 4 wherein said injector means includes a conduit disposed within said arbor and injector nozzles connected to said conduit.

10 6. The combination of claim 5 wherein said nozzles are disposed in vertically spaced relation within said filter unit.

15 7. The combination of claim 1 wherein said screen and baffle units each consists of a cylindrical wall having a transverse plate therein intermediate its ends, the plates of said screen units being each provided with a multiplicity of apertures, the plates of said baffle units each having a plurality of openings therethrough with said baffles being each mounted upon the periphery of one of said openings.

20 8. The combination of claim 7 including an arbor extending axially through said treater unit, each of said plates being mounted upon and encircling said arbor.

25 9. The combination of claim 8 wherein said injector means includes a conduit disposed within said arbor and injector nozzles connected to said conduit.

10 10. The combination of claim 9 wherein said nozzles are disposed in vertically spaced relation within said filter unit.

11. The combination of claim 2 wherein said filter unit comprises a plurality of vertically spaced rings having annular openings therebetween in the order of about one fifteen thousandth ($\frac{1}{15,000}$) inch and means disposed within said rings and fixedly retaining them in spaced relation.
